BOW COMPASS

Alexander P. Bartusch, Lockport, N. Y.

Application October 9, 1943, Serial No. 505,654

5 Claims. (Cl. 33—154)

1

This invention relates generally to certain new and useful improvements in drafting instruments but more particularly to bow compasses or dividers for draftsmen, mechanics, toolmakers and the like.

One of the objects of the invention is to provide an instrument of this character which is so designed as to be simple, sturdy and inexpensive in construction, which is accurate in operation, and which is light in weight and easy to manipulate.

It has for a further object to provide a compass having a novel, sectional, stamped leg construction of maximum rigidity and one which is not subject to sidewise or lateral deflection, and wherein the sections of each leg are rigidly secured in predetermined spaced relation between the pivotal and adjustable bearing points.

A still further object of the invention is to provide a drafting instrument having novel means for adjustably and detachably mounting the pivot or scribing point in a set position and for detachably securing thereto a pen or like attachment to the instrument.

Other features of the invention reside in the construction and arrangement of parts herein-after described and particularly pointed out in the appended claims.

In the accompanying drawings:

Figure 1 is a front elevation of the compass embodying my invention. Figure 2 is an end view thereof. Figures 3 and 4 are enlarged transverse sections taken on the correspondingly-numbered lines in Figure 1. Figure 5 is a front elevation of a modified form of the invention. Figure 6 is an end view thereof. Figures 7 and 8 are enlarged transverse sections taken on the correspondingly-numbered lines in Figure 5. Figure 9 is a fragmentary side elevation of another modification of the invention.

Similar characters of reference indicate corresponding parts throughout the several views.

Referring to Figures 1—4 inclusive of the drawings 10, 10 indicate a pair of legs pivoted at their upper ends to a transverse pivot pin 11 for adjustment toward and from each other, each leg consisting of a pair of companion sections of relatively thin material disposed in transversely spaced relation and notched at their upper ends for engagement with corresponding annular grooves 12 formed in the pivot pin. A substantially circular or loop-like spring 13 applied to the upper ends of the leg-sections serves to retain them on the pivot pin. These legs may be in the form of stampings and intermediate their upper and lower ends each pair of sections is

2

rigidly secured together against relative transverse displacement by a spacer member 14 which is provided with journals 15 resulting in outwardly-facing shoulders 16 disposed to abut against the opposing inner faces of the leg-sections, while their outer ends are upset or flanged, as indicated at 17 over the outer faces of such sections. While those portions of the companion leg-sections between the pivot and spacer members 11 and 14, respectively, are securely retained in parallel relation and against lateral deflection, the lower portions thereof below the spacer member are free to yield and to move toward and from each other to detachably receive therebetween a pivot or scribing point 18. As shown in Figure 2, these yieldable lower portions of the leg-sections converge somewhat immediately below the spacer member 14 and then continue downwardly in comparatively close parallel relation. On the inner faces of their terminal ends, these lower leg portions are provided with mating grooves 19 between which the pivot or scribing point is arranged. A clamping screw 20 is employed for anchoring each point in its set position of adjustment in the companion leg.

As shown in Figure 1, the inner edges of the legs of the compass are bowed inwardly slightly below the axes of the spacer members and then outwardly at their lower ends, so that the pivot and scribing points are in their most efficient working position and can be brought closely together to accurately describe the smallest of circles.

For the purpose of adjusting the compass legs toward and from each other an adjusting screw 21 is provided having a centrally-disposed actuating wheel 22, the opposite ends of the screw having right and left hand threads thereon engaging correspondingly threaded opening 23 formed in the spacer members 14 which function as nuts for causing the legs to move toward and from each other in accordance with the turning of the actuating wheel in one direction or the other. While these spacer members retain the leg-sections rigidly in spaced relation and prevent their lateral or transverse deflection during the scribing operation or when pressure is imposed on the hand wheel during adjustment of the compass, sufficient clearance is provided to permit such members to turn or swivel in response to the relative movements of the legs and the adjusting screw.

A finger-engaging stem 24 rises from the top of the compass centrally of its pivot pin 11, being secured at its lower end to the latter and passing

intermediate its ends through an opening in the spring 13.

In the modification of the invention shown in Figures 5-8, inclusive, the sectional leg structure is the same as in the previously-described construction and the parts thereof have been correspondingly numbered. However, the lower end of the compass is shown as equipped with a reversely adjustable double-ended pivot point 25 and with a detachable drafting tool 26, such as a ruling pen. In this form of the invention, the pivot point 25 is supported between grooved clamping plates 27 disposed in the space provided by the lower ends of one of the sectional legs and adapted to be held in a set position by a clamping screw 28 passing transversely through the leg-sections and the plates. By this construction, the pivot point 25 can be readily reversed without removing it from the compass, it being only necessary to loosen the clamping screw sufficiently to enable the companion plates 27 to be turned as a unit about the axis of such screw.

In adapting the compass to the use of drafting tools, such as the ruling pen 26, one of the sectional legs is shortened, as indicated at 29, and the tool has a coupling head or tongue 30 at its upper end for part-way lateral insertion in the space provided by the shortened leg. A clamping screw 31 passing through a threaded opening in the tongue and abutting at its headed end against the outer edges of the leg-sections serves to detachably retain the tool in its operative position. As shown in Figure 8, the shank 32 of the tool, from which the tongue 30 extends in a lateral direction, has outwardly-diverging shoulders 33 thereon at its junction with the tongue which abut against like beveled edges 34 formed on the adjoining portions of the leg-sections, whereby to securely clamp the parts in firm wedge-like engagement.

As shown in Figure 9, the ruling pen 35 may be adjustably pivoted at 36 in the space between the foreshortened end-sections 31 of one of the compass-legs.

I claim as my invention:

1. A compass of the character described, comprising a pair of legs pivoted at their upper ends for adjustment toward and from each other, each of said legs consisting of a pair of companion sections disposed in transversely spaced relation from their upper pivoted ends to the lower free ends thereof and adapted to receive in operative relation at such lower ends a pivot or scribing point, an adjusting screw spanning said legs for effecting their adjustment, and a combination spacer and nut member disposed between companion leg-sections intermediate their upper and lower ends for retaining them in fixed spaced relation and for operatively receiving the opposite ends of the adjusting screw, those portions of the legs below the retaining member being free to spring toward and from each other.

2. A compass of the character described, comprising a pair of legs pivoted at their upper ends for adjustment toward and from each other, each of said legs consisting of a pair of companion sections disposed in transversely spaced relation from their upper pivoted ends to the lower free ends thereof, an adjusting screw spanning said legs for effecting their adjustment, a combination spacer and nut member joined at its opposite ends to the companion leg-sections intermediate the upper and lower ends thereof for retaining them in fixed spaced relation in the axial plane of the adjusting screw pivot of the legs, the leg-sections

below said spacer and nut member being relatively free, and a clamping element applied to the lower extremities of the leg-sections for removably clamping a pivot or scribing point thereto.

5. A compass of the character described, comprising a pair of legs pivoted at their upper ends for adjustment toward and from each other, each of said legs consisting of a pair of companion sections disposed in transversely spaced relation from their upper pivoted ends to the lower free ends thereof, annularly-grooved members in supporting and space-governing relation to the companion sections of each leg, one of said members being disposed at the upper end of the legs and constituting the common pivot therefor and the other members being rotatably disposed below such pivot in parallel relation thereto and serving to retain the respective leg-sections in rigid spaced relation at a point intermediate their upper and lower ends, an adjusting screw spanning said legs and operatively connected at its ends to the companion lower leg-section retaining members, those portions of the leg-sections below the retaining members being free to yield and to relatively move toward and from each other, and clamping elements applied to the lower ends of such leg-sections for removably clamping a pivot or scribing point thereto.
10. A compass of the character described, comprising a pair of legs pivoted at their upper ends for adjustment toward and from each other, each of said legs consisting of a pair of companion sections disposed in transversely spaced relation from their upper pivoted ends to the lower free ends thereof, the retaining members being disposed at the upper ends of the leg-sections, the lower ends of the leg-sections being free to yield and to relatively move toward and from each other, and clamping elements applied to the lower ends of such leg-sections for removably clamping a pivot or scribing point thereto.
15. A compass of the character described, comprising a pair of legs pivoted at their upper ends for adjustment toward and from each other, each of said legs consisting of a pair of companion sections disposed in transversely spaced relation from their upper pivoted ends to the lower free ends thereof, an adjusting screw spanning said legs and operatively connected at its ends to the companion lower leg-section retaining members, those portions of the leg-sections below the retaining members being free to yield and to relatively move toward and from each other, and clamping elements applied to the lower ends of such leg-sections for removably clamping a pivot or scribing point thereto.
20. A compass of the character described, comprising a pair of legs pivoted at their upper ends for adjustment toward and from each other, each of said legs consisting of a pair of companion sections disposed in transversely spaced relation from their upper pivoted ends to the lower free ends thereof, a pivot member in supporting and space-governing relation to the upper ends of the companion sections of said pair of legs, a spacer member disposed between the companion sections of each leg at a point intermediate the upper and lower ends thereof, said spacer member being free to turn about an axis parallel to the pivot member and flanged at its opposite ends over said leg-sections to retain them in fixed spaced relation, those portions of the leg-sections below the retaining spacer member being contracted in parallel spaced relation and free to spring toward and from each other, and clamping elements applied to the lower ends of the leg-sections for removably clamping a pivot or scribing point thereto.
25. A compass of the character described, comprising a pair of legs pivoted at their upper ends for adjustment toward and from each other, each of said legs consisting of a pair of companion sections disposed in transversely spaced relation from their upper pivoted ends to the lower free ends thereof, a pivot member in supporting and space-governing relation to the upper ends of the companion sections of said pair of legs, a spacer member disposed between the companion sections of each leg at a point intermediate the upper and lower ends thereof, said spacer member being free to turn about an axis parallel to the pivot member and flanged at its opposite ends over said leg-sections to retain them in fixed spaced relation, those portions of the leg-sections below the retaining spacer member being contracted in parallel spaced relation and free to spring toward and from each other, and clamping elements applied to the lower ends of the leg-sections for removably clamping a pivot or scribing point thereto.
30. A compass of the character described, comprising a pair of legs pivoted at their upper ends for adjustment toward and from each other, each of said legs consisting of a pair of companion sections disposed in transversely spaced relation from their upper pivoted ends to the lower free ends thereof, a pivot member in supporting and space-governing relation to the upper ends of the companion sections of said pair of legs, a spacer member disposed between the companion sections of each leg at a point intermediate the upper and lower ends thereof, said spacer member being free to turn about an axis parallel to the pivot member and flanged at its opposite ends over said leg-sections to retain them in fixed spaced relation, those portions of the leg-sections below the retaining spacer member being contracted in parallel spaced relation and free to spring toward and from each other, and clamping elements applied to the lower ends of the leg-sections for removably clamping a pivot or scribing point thereto.
35. A compass of the character described, comprising a pair of legs pivoted at their upper ends for adjustment toward and from each other, each of said legs consisting of a pair of companion sections disposed in transversely spaced relation from their upper pivoted ends to the lower free ends thereof, a pivot member in supporting and space-governing relation to the upper ends of the companion sections of said pair of legs, a spacer member disposed between the companion sections of each leg at a point intermediate the upper and lower ends thereof, said spacer member being free to turn about an axis parallel to the pivot member and flanged at its opposite ends over said leg-sections to retain them in fixed spaced relation, those portions of the leg-sections below the retaining spacer member being contracted in parallel spaced relation and free to spring toward and from each other, and clamping elements applied to the lower ends of the leg-sections for removably clamping a pivot or scribing point thereto.
40. A compass of the character described, comprising a pair of legs pivoted at their upper ends for adjustment toward and from each other, each of said legs consisting of a pair of companion sections disposed in transversely spaced relation from their upper pivoted ends to the lower free ends thereof, a pivot member in supporting and space-governing relation to the upper ends of the companion sections of said pair of legs, a spacer member disposed between the companion sections of each leg at a point intermediate the upper and lower ends thereof, said spacer member being free to turn about an axis parallel to the pivot member and flanged at its opposite ends over said leg-sections to retain them in fixed spaced relation, those portions of the leg-sections below the retaining spacer member being contracted in parallel spaced relation and free to spring toward and from each other, and clamping elements applied to the lower ends of the leg-sections for removably clamping a pivot or scribing point thereto.
45. A compass of the character described, comprising a pair of legs pivoted at their upper ends for adjustment toward and from each other, each of said legs consisting of a pair of companion sections disposed in transversely spaced relation from their upper pivoted ends to the lower free ends thereof, a pivot member in supporting and space-governing relation to the upper ends of the companion sections of said pair of legs, a spacer member disposed between the companion sections of each leg at a point intermediate the upper and lower ends thereof, said spacer member being free to turn about an axis parallel to the pivot member and flanged at its opposite ends over said leg-sections to retain them in fixed spaced relation, those portions of the leg-sections below the retaining spacer member being contracted in parallel spaced relation and free to spring toward and from each other, and clamping elements applied to the lower ends of the leg-sections for removably clamping a pivot or scribing point thereto.
50. A compass of the character described, comprising a pair of legs pivoted at their upper ends for adjustment toward and from each other, each of said legs consisting of a pair of companion sections disposed in transversely spaced relation from their upper pivoted ends to the lower free ends thereof, a pivot member in supporting and space-governing relation to the upper ends of the companion sections of said pair of legs, a spacer member disposed between the companion sections of each leg at a point intermediate the upper and lower ends thereof, said spacer member being free to turn about an axis parallel to the pivot member and flanged at its opposite ends over said leg-sections to retain them in fixed spaced relation, those portions of the leg-sections below the retaining spacer member being contracted in parallel spaced relation and free to spring toward and from each other, and clamping elements applied to the lower ends of the leg-sections for removably clamping a pivot or scribing point thereto.
55. A compass of the character described, comprising a pair of legs pivoted at their upper ends for adjustment toward and from each other, each of said legs consisting of a pair of companion sections disposed in transversely spaced relation from their upper pivoted ends to the lower free ends thereof, a pivot member in supporting and space-governing relation to the upper ends of the companion sections of said pair of legs, a spacer member disposed between the companion sections of each leg at a point intermediate the upper and lower ends thereof, said spacer member being free to turn about an axis parallel to the pivot member and flanged at its opposite ends over said leg-sections to retain them in fixed spaced relation, those portions of the leg-sections below the retaining spacer member being contracted in parallel spaced relation and free to spring toward and from each other, and clamping elements applied to the lower ends of the leg-sections for removably clamping a pivot or scribing point thereto.
60. A compass of the character described, comprising a pair of legs pivoted at their upper ends for adjustment toward and from each other, each of said legs consisting of a pair of companion sections disposed in transversely spaced relation from their upper pivoted ends to the lower free ends thereof, a pivot member in supporting and space-governing relation to the upper ends of the companion sections of said pair of legs, a spacer member disposed between the companion sections of each leg at a point intermediate the upper and lower ends thereof, said spacer member being free to turn about an axis parallel to the pivot member and flanged at its opposite ends over said leg-sections to retain them in fixed spaced relation, those portions of the leg-sections below the retaining spacer member being contracted in parallel spaced relation and free to spring toward and from each other, and clamping elements applied to the lower ends of the leg-sections for removably clamping a pivot or scribing point thereto.
